Des. 205,968
Patented Oct. 11, 1966

205,968

COMBINED PACKAGING CONTAINER AND COVER

John Donald Bostrom, 8251 N. Oleander, Niles, Ill.

Filed Aug. 18, 1965, Ser. No. 86,633

Term of patent 14 years

(Cl. D58—12.6)

Fig. 1

Fig. 2

Fig. 3

Fig. 4

Fig. 5

FIG. 1 is a perspective view of a combined packaging container and cover embodying my new design;

FIG. 2 is a top plan view thereof on a reduced scale;

FIG. 3 is a bottom plan view on the same scale as FIG. 2;

FIG. 4 is a side elevational view on the same scale as FIG. 2; and

FIG. 5 is an end elevational view on the same scale as FIG. 2.

I claim:

The ornamental design for a combined packaging container and cover, as shown.
